UNITED STATES PATENT OFFICE.

JAMES H. GOODIER, OF NEW YORK, N. Y.

ENVELOPE CLOSURE.

Application filed June 14, 1921. Serial No. 477,443.

To all whom it may concern:

Be it known that I, JAMES H. GOODIER, a citizen of the United States, residing at New York (Hotel Belleclaire, Broadway at 77th St.), in the county of New York and State of New York, have invented certain new and useful Improvements in Envelope Closures, of which the following is a specification.

This invention relates to envelope closures, and it comprises a seal, a tongue or ribbon secured to the seal centrally thereof, said tongue being attached to the inside of one of the flaps of the envelope, the seal being adapted to be secured over the flaps of the envelope at the closure when the envelope is sealed.

An object of the present invention is the provision of a distinctive seal for closing an envelope to replace the wax seal now commonly used when extra precaution is taken to secure inviolability of an envelope's contents.

A further object is the provision of a distinctive seal which forms an integral part of the envelope and is always at hand, eliminating the necessity of obtaining a seal from a separate source when the envelope is to be closed and securing the same to the envelope. The seal may be made in varying sizes and any desired design may be applied to the surface thereof, such as a family crest, a corporate seal, or other desirable design. When the envelope is closed, the seal is arranged over the closure, necessitating breaking the seal to open the envelope.

In the accompanying drawings, I have shown several embodiments of the invention.

40 In this showing:

Figure 1 is a rear elevation of an envelope showing the invention applied.

Figure 2 is a transverse sectional view on line 2—2 of Figure 1,

45 Figure 3 is a rear elevation illustrating the use of a plurality of seals.

Figure 4 is a view of an envelope blank showing a seal formed integral therewith, and,

50 Figure 5 is a perspective view of the envelope ready for sealing.

Referring to the drawing, the reference numeral 1 designates the front of an envelope, provided with a bottom flap 2, a top flap 3, and side flaps 4. The envelope is assembled in the usual manner by providing

flaps sufficiently large to slightly overlap when folded and the bottom flap is adapted to be sealed or glued to the overlapping portions of the side flaps in the usual manner. 60 When the envelope is to be closed, the top flap is arranged over the overlapping portion of the side flaps and bottom flap and sealed.

The sealing device forming the subject matter of the present invention comprises a seal 5, having a tongue or ribbon 6 secured thereto centrally of the seal, the tongue or ribbon extending into the envelope and being secured to the inside of the 70 bottom flap, as at 7. When the envelope is to be used, the tongue is extended between the top and bottom flaps, as represented at 8, in Figure 2 of the drawings, and then arranged with the end of the tongue adjacent 75 the lower end of the top flap when the top flap is in closed position. The seal 5 will then be disposed partly over the top flap and partly over the lower flap, covering the point of closure between the top and bottom 80 flaps. The seal may be provided with glue or other suitable adhesive to secure it to the top and bottom flaps.

In Figure 3 of the drawings, there is shown a central seal 5, and a plurality of 85 seals 9, arranged between the central seal and the side edges of the envelope. The construction of the outer seals 9 is in all respects similar to the seal 5, and they are secured to the envelope in the same manner. 90

In the form of the invention shown in Figure 4 of the drawings, the seal 10 is made integral with the bottom flap of the envelope, and is connected thereto by means of a tongue 11. When the envelope is folded the tongue 11 is arranged between the top and bottom flaps as in the form heretofore disclosed and the seal is arranged overlapping the top and bottom flaps and secured to each of them.

It will be apparent that the present construction provides an envelope seal which may be readily and quickly applied, the seal being at all times attached to the envelope and ready for use. When the seal is in position, the top flap 3 of the envelope cannot be opened without breaking it, and it may thus be employed in place of wax or other sealing devices now in use.

110 It is to be understood that the forms of my invention herewith shown and described are to be taken as preferred examples of the

same, and that various changes in the shape, size, and arrangement of parts may be resorted to without departing from the spirit of the invention or the scope of the subjoined claims.

Having thus described my invention, I claim:

- 10 1. An envelope having side flaps, a top flap, and a bottom flap, a tongue secured to the inner side of the bottom flap, and a seal carried by said tongue adapted to be arranged over the overlapping portions of the top flap and bottom flap when the envelope is closed.
- 15 2. An envelope having side flaps, a top flap, and a bottom flap, a tongue secured to the inside of the bottom flap, and adapted to extend over the bottom flap, when the envelope

lope is closed, and a seal carried by said tongue adapted to be arranged over the overlapping portions of the top and bottom flaps.

3. An envelope having side flaps, a top flap, and a bottom flap, a tongue secured to the inside of the bottom flap, and adapted to 25 extend over the bottom flap when the envelope is closed, a seal carried by said tongue adapted to be arranged over the overlapping portions of the top and bottom flaps, and means for securing said seal to the envelope. 30

In testimony whereof I affix my signature in presence of two witnesses.

JAMES H. GOODIER.
